UNITED STATES PATENT OFFICE.

ZOLA B. MOORE, OF LOS ANGELES, CALIFORNIA.

UNDERGARMENT.

Application filed October 23, 1918. Serial No. 259,440.

To all whom it may concern:

Be it known that I, ZOLA B. MOORE, a citizen of the United States, residing at 2652 South Hoover Street, in the city of Los Angeles, county of Los Angeles, and State of California, have invented a new and useful Undergarment, of which the following is a specification.

My invention relates to improvements in 10 drawers and union suits comprising a body having legs united by a permanently closed crotch and having an open-front and an opening in the rear and are made of any suitable material, for the use of males only. 15 It is adapted to use by applying a certain reinforcement at the front of said garments. My invention is made of material such as that of a garment cut in such shape that it protects the garment on each side of the 20 middle opening high enough above the crotch and low enough into the seat, to prevent the male organs coming into contact with any part of the garment which is of only one thickness. This reinforcement is 25 placed on the inside by preference. This lengthens the life of the garment many times. Garments heretofore worn by males without this reinforcement have been subject to break down at this point in a short 30 time, when the rest of the garment shows no wear. Not only is the long life or wear of the garment a valuable thing, but the firm support afforded, by this invention is conducive to great comfort to the wearer as it 35 prevents the usual sagging on the side upon which the male dresses himself.

This invention relates to an under-garment for males, and particularly to the class including reinforced nether undergarments.

An object of the invention is to provide 40 an under-garment of this character which will be superior in ease and comfort to the wearer, and will also afford superior wear and longer life of garment with minimum 45 amount of material.

An object of this invention is to produce 50 a great saving of garments by eliminating wear which heretofore has been so destructive to men's garments.

Furthermore, men's union-suits are subject to become loose and baggy at the front just about the level and below the level of 55 the crotch on account of the peculiar strains

upon that portion of the garment caused by the masculine anatomy, and an object of this 55 invention is to construct a union suit which will more perfectly retain its form than with garments of this kind heretofore manufactured.

Another object of the invention is to so 60 construct a simple union-suit or light under-garment for men that the same will operate as a substitute for suspensories now worn by men and will afford to the wearer the comfort and ease which such suspensories are 65 intended to afford to those of the male sex not engaged in sedentary pursuits and yet will be neat-fitting, soft and pliable and will yield ready access to the organs in the quickest and simplest way. 70

I have discovered that without making the garment clumsy or uncomfortable all of these objects can be attained by very simple and inexpensive means; viz, the application to the garment of a reinforcing piece of material which may preferably be of the same character as that of the garment and which extends over that front portion of the garment which contacts with the male organs. 75

In cases where the wearer invariably 80 dresses on one side only, it would be sufficient to apply a reinforcing piece to that side only of the garment on which he dresses, but owing to the fact that the male may dress on either side I provide a piece which extends upon both sides of the front midline so as to accommodate both modes of dressing. 85

An object of this invention is to make provision whereby both styles of masculine 90 dressing may be accommodated by a well fitting garment that will hold its form, resist wear, and support the dependencies of the male anatomy.

It is noted that at times of certain excitement and at other times in vigorous young men the strain and wear upon the material of the garment by one of the male organs is at a considerable level above the crotch but close to the midline of the garment. 95

The invention is broadly new and pioneer in that there has never heretofore been any close fitting under-garment provided with a reinforcing piece adapted to receive and sustain the direct pressure of such sex organ of 100 the wearer under such conditions. 105

This invention includes the reinforced undergarment and also the construction of the reinforcing piece.

Other objects, advantages and features of invention may appear in the accompanying drawing, the subjoined detail description and the appended claims.

The accompanying drawing illustrates the invention.

Figure 1 is a front view of a union-suit constructed in accordance with this invention.

Fig. 2 is a plan on an enlarged scale at line x^2 of the union-suit shown in Fig. 1.

Fig. 3 is a section on line x^3 Figs. 1 and 2.

Fig. 4 is a plan of the duplex reinforcing piece.

Fig. 5 is a view of a construction in which the reinforcing piece is applied outside of the material of the main body of the garment.

The garment may be of any knit, woven or other material suitable for drawers or union-suits of under-wear, and comprises the body 1, and the legs 2, 3, united by the permanently closed crotch 4, all of the usual construction permanent closed-crotch undergarments. The reinforcement 5 is preferably of substantially the same kind of material as the garment at the place where said garment is reinforced, and constitutes a comfort patch conformed to the garment at one or both sides of the front midline opening thereof, and extending over sufficiently to accomplish the purpose above outlined, and stitched by stitches 6, at its edges to the material of the garment and also extending downwardly on the inside of the legs and over the usual crotch seam 7, behind which it extends in a transverse ogee curve 8, to both ends of the rear central point 9, and one side of said downwardly extending portions terminating at the lower edge of the rear opening of the garment.

Said reinforcing piece in practice consists of a patch one end of which is in the form of a parabola which is slit at d to form two lobes a, b . The other end of the patch is spaced some distance from the end of the slit to form a neck c which connects the lobes at their lower portion when the garment is positioned with the body up and legs down. The lower end of said patch curves centrally on each side of the produced line of said slit, in the form of an ogee curve and thereby forms a recess at the central point 9, which recess terminates at some distance from the inner end of said slit, to form the neck c . The two ogee curves on the lower edge of the patch terminate at the produced line of said slit.

In practice the reinforcing piece may be stamped in quantities from material of the same general character as that of the garment body and after the garment has been

made in the usual manner of manufacturing, the reinforcing piece will be preferably applied to the inside of the garment and extends from the lower edge of the closed-crotch forwardly and upwardly for a considerable distance on both sides of the open-front to reinforce that portion of the garment which is subject to the wear and strain as set forth. The edges of said piece are appropriately stitched or otherwise permanently fastened to the body material of the garment; the edges of the slit being fastened to the edges f, g , of the front opening h of the garment. When the piece has thus been fastened to the inside face of the garment, said garment is ready for wear.

In practical use the reinforcing piece supported by the garment proper receives the pressure and the wear of the male organs, irrespective of the side on which the wearer dresses; with the result that a superior sense of comfort is given to the wearer and the life of the garment is very greatly increased. The support is effective to both the front and undersides of the organs to be supported, and particularly to the front and under surface of the central organ under conditions which are likely to frequently occur, and the strain upon the garment is relieved so that it does not break away nor become loose and baggy.

I do not intend to confine the invention to the garment in which the reinforcing piece is fastened to the inner side as distinguished from the outer side of the garment body, although the construction with the reinforcement inside is preferable on account of the neatness of appearance and the direct contact of the male organs and the direct reception of the strain that is applied on the inside as contradistinguished from the outside of the garment body.

I claim,

1. An undergarment for men comprising a body having legs united by a permanently closed-crotch and having an open-front and an opening in rear; a reinforcing patch fastened to the garment and extending upwardly on the front of said garment from about the level of the crotch and the middle thereof to a considerable distance above the crotch and the lower edge of said open-front and a short distance at each side of the middle of said open-front, and downwardly on the inside of the legs of said garment and over the usual crotch seam, and one side of said downwardly extending portions terminating at the lower edge of the rear opening; and said reinforcements being adapted to receive the wear and strain occasioned by the central male organ substantially as set forth.

2. A garment comprising a body and legs permanently united by a closed-crotch, and having a rear opening, and an open-front

somewhat above the crotch; and a reinforcing piece formed of a neck and two lobes, the lower edge of the neck being in the form of a double ogee curve and being fastened 5 to the garment at the lower edge of the rear opening and the two lobes extending upwardly for a distance of at least the width of said neck on opposite sides of the front opening of the garment and being fastened thereto, said reinforcing piece receiving 10 wear and strain imposed by the central organ of the male anatomy.

In testimony whereof, I have hereunto set my hand at Los Angeles, California, this 16 day of October, 1918.

ZOLA B. MOORE.
